UNITED STATES PATENT OFFICE.

JOHN OSCAR EMRICH, OF ALLEGHENY, PENNSYLVANIA.

METALLIC DOOR.

No. 876,788.

Specification of Letters Patent.

Patented Jan. 14, 1908.

Application filed July 3, 1907. Serial No. 382,106.

To all whom it may concern:

Be it known that I, JOHN OSCAR EMRICH, a resident of Allegheny, in the county of Allegheny and State of Pennsylvania, have invented a new and useful Improvement in Metallic Doors; and I do hereby declare the following to be a full, clear, and exact description thereof.

My invention relates to a metallic or fire-proof door, and has for its object the construction of such a door by combining sheet steel, wire glass and other fire retarding materials in a novel and effective manner for the purpose of forming such a door.

A further object of my invention is to effect such a result at an economical cost on account of the simplicity of construction of the steel parts, and of the manner of combining the same with the other fire retarding elements used therewith.

The following is a clear and concise description of my preferred form of construction, reference being had to the accompanying drawings, in which:

Figure 1 is a sectional elevation of my invention. Fig. 2 is a horizontal section on lines 2—2 of Fig. 1. Figs. 3 and 4 are similar views on lines 3—3 and lines 4—4 respectively of Fig. 1. Fig. 5 is a view in perspective, showing the construction of the door particularly at the point of abutment or connection with the stiles. Fig. 6 is a perspective view of a clamp adapted to bind together the rails and stiles. Fig. 7 is a perspective view of a section of a stile showing its construction and adaptability for engagement by the clamp. Fig. 8 shows, in perspective, a slotted pin fitted with keys and set screws. Fig. 9 is a plan or top view of a lock carrier or support.

Like references in the specification refer to like parts in the drawings, in which 1 represents an outer hollow stile.

2 represents an outer hollow rail, both of which are preferably made of sheet steel, each having a marginal angular formation 3 on each side thereof. The adjoining or abutting parts of said outer stiles and rails being turned inwardly to form the obtuse angles 4 (Fig. 5 and 7) which are adapted to be engaged by the clamps 5, as shown in Fig. 3, being inserted through the opening 6 of the stiles 1 and open end 7 of the rail 2, the obtuse angles 4 and clamp 5 being thoroughly clamped together to effect a perfect junction of the outer stiles and outer rails as shown in

Figs. 1 and 3, after which the part 8 is forced down closing the open corner 7 of the outer rail 2, and the part 9 is forced over to close the open end 6 of the outer stile 1, the parts 8 and 9 being held in fixed closed position by suitable machine screws inserted through the holes 10 and engaging a suitable nut (not shown) on the under side of the parts 8 and 9. Within the outer stiles and rails are inner hollow stiles 11 and inner hollow rails 12, each having a marginal angular formation surrounding the space between said inner stiles 11 and inner rails 12 and forming an inner frame 13. The inner stiles and rails are made preferably of a size and form to be out of contact with the walls of the outer stiles and rails except at the hinge bearing points and marginal angle of the outer stile or rail where the inner stile is extended, folded and carried against the depressed hinge bearings point 14 on the outer stile 1 for the purpose of reinforcing those parts, as shown at 15, in Fig. 2.

Attached to or carried by the inner stile is a lock carrier or support 16 (Fig. 9) adapted to carry a lock independently of the outer stile, the opening 17 therein and the opening 18 in the outer stile permitting the communication between the lock and a keeper in a jamb. In each of said inner stiles and rails fire-retarding materials, preferably a sheet of wire glass 19 and sheets of asbestos 20 one on each side thereof, the glass 19 and asbestos 20 being long enough to occupy the ends of the inner rails which are mortised in the ends of the inner stiles and fixedly secured in position by the pins 21 having slots 22 therein and keys 23 held in position in the slots by set screws 24.

In the inner frame 13 is a sheet of wire glass 25 which may be held in place by cleats 26 one end of which are secured to the angle 3 of the outer stiles and rails, the other end of said cleats being arranged to bear against the sheet of glass to support the same (Fig. 4). The outer and the inner stiles and rails and the fire-retarding material within the inner stiles and rails are finally tied rigidly together by pins 21 being inserted through said structure at the angle 3, and keys 23 at both ends, the keys being secured in position by set screws 24, as heretofore described, (Fig. 4). The molding 28 is then put in position and readily secured therein by suitable machine screws engaging the tapped hole 29.

It is clear that the construction of the outer stiles and rails may be modified and the form of the inner stiles and rails may be changed so as to distribute the space between the inner and outer stiles differently or combine the same by clamps, and the arrangement of the glass and other fire retarding material may be modified without departing from the spirit of my invention.

10. What I claim as my invention and desire to secure by Letters Patent, is:—

1. In a metallic door inner hollow stiles and rails, having outer stiles and rails, an inner frame formed around the margin of the space between the inner stiles, pins adapted to engage the stiles and rails, and means connected to the ends of the pins for holding the parts in fixed position.

2. In a metallic door inner hollow stiles and rails, and outer stiles and rails, an inner frame formed around the margin of the space between the inner stiles, pins adapted to engage the stiles and rails, and means for supporting a molding or finish at each end of said pins.

3. In a metallic door inner hollow stiles and rails, and outer stiles and rails, the outer stile having interiorly reinforced hinge bearings, pins extending through said stiles and rails, and means connected to the ends of the pins for supporting the parts compactly together.

4. In a metallic door inner hollow stiles and rails, and outer stiles and rails, a lock carrier or support carried on the inner stile, pins extending through said stiles and rails, and means connected to the ends of the pins for supporting the parts compactly together.

5. In a metallic door inner hollow stiles and rails, and outer stiles and rails, the outer stile having interiorly reinforced hinge bearings, a lock carrier or support within the outer stile, pins engaging the stiles and rails and means connected to the ends of the pins for supporting the parts compactly together.

6. In a metallic door inner hollow stiles and rails, and outer stiles and rails, an inner frame formed around the margin of the plane between the stiles, a sheet of fire retarding material in said inner frame, pins adapted to engage the stiles and rails, and means connected to the ends of the pins for holding the parts fixedly together.

7. In a fire door inner hollow stiles and rails, and outer stiles and rails, the outer stile having interiorly reinforced hinge bearings, an inner frame surrounding the space between the stiles, fire-retarding material in said frame, pins adapted to engage the stiles and rails, and means connected to the ends of the pins for holding the same in fixed position.

8. In a fire door inner hollow stiles and rails, and outer stiles and rails, the outer stile

having interiorly reinforced hinge bearings, 65 a lock carrier or support within the outer stile, an inner frame surrounding the space between the stiles, fire retarding material in said inner frame, pins adapted to engage the stiles and rails, and means connected to the 70 ends of the pins for holding the same in fixed position.

9. In a fire-proof door inner hollow stiles and rails having fire-retarding material arranged therein, pins extending through said 75 inner stiles and rails and fire retarding material, and means engaging the ends of the pins for holding the parts in fixed position, a frame between said stiles and fire retarding material in said frame, outer stiles and rails, 80 and pins engaging the inner and outer stiles and rails to combine said parts compactly together.

10. In a fire-proof door, inner stiles and rails having an angular form surrounding the 85 space between said stiles to serve as an inner frame, a sheet of fire retarding material within each inner stile and rail and inner frame, cleats adapted to engage the fire retarding material in the inner frame, outer stiles and rails, and pins having means connected thereto for holding the structure compactly together.

11. In a fire-proof door, inner stiles and rails having an angular form surrounding the 95 space between said stiles to serve as an inner frame, fire retarding material within each inner stile and rail and inner frame, cleats adapted to engage the fire retarding material in the inner frame, outer stiles and rails, and 100 slotted pins having means communicating therewith for holding the structure compactly together.

12. A fire-proof door, comprising inner hollow stiles and rails, fire retarding material 105 within each of said stiles and rails, an inner frame surrounding the space between the stiles, fire retarding material in said inner frame, pins combining said stiles and rails, outer stiles and rails engaged by suitable 110 clamps, and slotted pins having means engaging the ends thereof to support the structure in fixed position.

13. In a metallic door, the combination of inner stiles and rails forming an inner frame 115 around the space between the stiles thereof, a sheet of fire retarding material within each of said stiles and rails and inner frame thereof, an outer frame inclosing the inner stiles and rails, with an intervening air-space, and means engaging the sides of the outer frame 120 for holding the structure compactly together.

In testimony whereof I, the said JOHN OSCAR EMRICH, have hereunto set my hand.

J. OSCAR EMRICH.
